UNITED STATES PATENT OFFICE.

GUSTAV FUCHS, OF CHICAGO, ILLINOIS.

DESIGN FOR AN ADVERTISING-STAFF.

SPECIFICATION forming part of Design No. 18,188, dated March 20, 1888.

Application filed February 3, 1888. Serial No. 262,940. Term of patent 14 years.

To all whom it may concern:

Be it known that I, GUSTAV FUCHS, a citizen of the United States of America, residing at Chicago, in the county of Cook and State of Illinois, have invented and produced a new and original Design for Advertising Staffs, of which the following is a specification, reference being had therein to the accompanying drawing.

The drawing represents a perspective view of my advertising-staff, representing a telegraph-wire support.

A denotes the staff, being fixed to a wall-bracket, B, which is shaped like a human arm, the hand of which grasping such staff.

15 C C C are boards secured at their middle transversely against the upper portion of the post, to be parallel with each other. These boards C C C are of decreasing lengths toward the top, and each has fastened upon its

upper edge a series of bells or shields, a, in 20 outline shaped like the insulating glass thimbles that are generally used for holding telegraph-wires. Such a bell or shield is also secured upon the upper extremity of the post.

I claim—

25 The design for an advertising-staff representing a telegraphic-wire support, and consisting of staff A, held by the human-arm-shaped bracket B, and transverse sign-boards C, with shields or bells a, all substantially as 30 herein shown and described.

In testimony whereof I affix my signature in presence of two witnesses.

GUSTAV FUCHS.
